CLAIM

The ornamental design for an ergonomic end cap, as shown and described.

DESCRIPTION

FIG. 1 is a perspective view of an ergonomic end cap showing my new design;

FIG. 2 is a side view of the ergonomic end cap, with all side views being identical;

FIG. 3 is a top view of the ergonomic end cap of FIG. 1;

FIG. 4 is a bottom view of the ergonomic end cap of FIG. 1;

FIG. 5 is a perspective view of another embodiment of the ergonomic end cap, showing my new design;

FIG. 6 is a side view of the ergonomic end cap of FIG. 5, with all side views being identical;

FIG. 7 is a top view of the ergonomic end cap of FIG. 5; and,

FIG. 8 is a bottom view of the ergonomic end cap of FIG. 5.
